UNITED STATES PATENT OFFICE.

CHESTER B. TURNER, OF DETROIT, MICHIGAN.

RELIEF-VALVE FOR ENGINES.

SPECIFICATION forming part of Letters Patent No. 326,070, dated September 8, 1885.

Application filed June 4, 1885. (No model.)

To all whom it may concern:

Be it known that I, CHESTER B. TURNER, of Detroit, in the county of Wayne and State of Michigan, have invented new and useful 5 Improvements in Relief-Valves for Steam-Engines; and I do hereby declare that the following is a full, clear, and exact description thereof, reference being had to the accompanying drawing, which forms a part of this 10 specification.

This invention relates to certain new and useful improvements in the construction and operation of relief-valves in the slide-valves of steam-engines, whether such valves have 15 a lap or not.

In all steam-engines liable to have the steam form a compressed cushion against the advance of the piston such compressed steam is apt to offer a great resistance to such advance of the 20 piston, and frequently such resistance is greater than the steam-pressure on the boiler. When this occurs, it produces a great strain on the engine and a loss of developed power, as so much power is required to overcome such 25 resistance. I provide relief by means of a check valve or valves seated in a passage or 30 passages in the slide-valve, which afford communication between the port or ports leading to the ends of the cylinder of the engine and the steam-space outside such valve in the steam-chest.

The invention consists in the peculiar construction, arrangement, and adaptation of parts, as will be more fully hereinafter set 35 forth, and specifically pointed out in the claim.

The figure is a section of a stationary steam-

engine, showing the steam-chest slide-valve without a lap, and the ports leading from the steam-chest to the ends of the cylinder.

In the accompanying drawing, A represents the steam-chest, B the ports leading therefrom to the cylinder, and C the slide-valve. D is a check-valve located in the center of the slide-valve. The moment the compression of steam in the cylinder and in advance of the piston is greater than the boiler-pressure in the steam-chest it will open the check-valve and afford immediate relief. The valve D is held between the valve C and a removable cap, C', secured thereon. This cap 45 limits the action of the valve and prevents it from rubbing against the roof of the steam-chest when the valve C is moving.

I exhaust from the cylinder by means of independent valves. (Not shown.)

It is obvious that this arrangement is especially adapted for engines where the main valve is used as a cut-off by means of a link-motion or otherwise.

I am aware of Patent No. 110,490, and do not seek to cover such construction in this application.

What I claim as my invention is—

The combination, with the steam-chest A and cylinder having ports B, of the slide-valve 65 C, having removable cap C'; and the relief-valve D, operating loosely between said valve and cap, as set forth.

CHESTER B. TURNER.
